UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

MACHINE FOR EMBOSSED HEELS ON SHOES.

1,030,608.

Specification of Letters Patent.

Patented June 25, 1912.

Application filed August 5, 1910. Serial No. 575,801.

To all whom it may concern:

Be it known that I, ADAM H. PRENZEL, a citizen of the United States, and a resident of Halifax, in the county of Dauphin 5 and State of Pennsylvania, have made certain new and useful Improvements in Machines for Embossing Heels on Shoes, of which the following is a specification.

My invention relates to devices for embossing heels on shoes, and it consists in the constructions, combinations and arrangements herein described and claimed.

An object of my invention is to provide a device which may be used advantageously 15 in the manufacture of shoes, more especially children's shoes, and in which the operation of making the heel may be effected with far less labor, and in a much shorter time than heretofore.

20 A further object of my invention is to provide a special form of die by means of which the embossing operation may be carried out.

25 Other objects and advantages will appear in the following specification and the novel features of the device will be particularly pointed out in the appended claims.

30 My invention is illustrated in the accompanying drawings in which—

Figure 1 shows a side view of the machine and its manner of use, Fig. 2 shows a front view of the machine, Fig. 3 is a front view of the upper die used in the embossing operation, Fig. 4 is a sectional view through the 35 upper die along the line 4—4 of Fig. 3, Fig. 5 is a bottom plan view of the upper die, Fig. 6 is a side view of the lower die, Fig. 7 is a main view of the lower die, and Fig. 8 is a plan view of the lower die.

40 In carrying out my invention, I provide a main frame 1 (see Fig. 1) having journaled thereon a rotary die holder 2. This die holder may be set in various positions by tightening up, or loosening, the nuts 3. 45 At the bottom part of the frame is an extension 4 which is bored to receive the sliding post 6. The latter carries a spring 5, which bears on the under side of the extension 4, so as to keep the post in a normally depressed position. The post 6 bears at its 50 top an integral arm 7, which is bored out to admit the reduced portion 8 of a die support 9. Between the reduced portion 8 and a reduced extension 4^a of the part 4 I place 55 a spring 10. A guide member 11 with a

stop nut 12 is secured to the extension 7 and is arranged to pass through the part 4^a for limiting the upward movement of the post 6. The die holder 9 bears on the upper portion of the part 7 and may be rotated around the axis of the reduced portion 8. It is provided with a stop pin 13 adapted to engage a stop 14 secured to the member 7. When the stop pin 13 is against the member 14, the lower die is immediately beneath the upper die. The dies used in connection with this device are best illustrated in Figs. 3-8 inclusive. The upper die is provided with a post 15 arranged to be inserted in the die holder 2. This post is integral with an upper portion 16 bearing at each end regulating set screws 17 and 18, respectively. The lower portion 19 forms the die proper. It is provided with upwardly extending portions 19^a and 19^b arranged to straddle the portion 16 to which it is pivoted by means of a pivot pin 20. It is apparent that the members 16 and 19 may be adjusted relatively to one another by means of the set screws 17 and 18. The bottom part of the die 19 is provided with a plate 21, which is secured to the member 19 by means of the screws 22. This plate is recessed at 23, and is of a heel shape. It will be noted that the recess is provided with a beveled portion 23^a near one end thereof, this portion being designed to form the beveled surface which connects the heel proper with the sole and which corresponds to the breast end of an ordinary heel. It will be noted that there is a beveled portion 23^b extending around the edge of the recess. The beveled portion 23^b operates to exert a lateral pressure upon the heel end of the sole, thereby vertically extending or thickening said edge during the embossing operation. This improves the appearance of the embossed heel and serves to give the impression that the heel is thicker than the other parts of the sole.

100 In Figs. 6, 7 and 8 I have shown the lower die-member 24. The lower die-member has a surface of a shape similar to that of the recess in the upper die member. The lower die member is somewhat smaller than the recess in the upper die member to allow for the thickness of the material coming between the die members during the embossing operation. Around the edge of the lower die member is a channel 24^a. The 110

purpose of this channel is an important one. I have found that in the operation, which will be subsequently explained, unless this channel is provided the shoe is liable to be injured. The die 24 is recessed at 24^b (see Figs. 6 and 7) and a coiled spring 25 is disposed therein and held by means of a screw plug 26 in the bottom of the die member. The spring 25 bears on the head 27^a of a pin 27, keeping the pin normally in a raised position, such as that shown in Fig. 6. A similar pin 28 having similar means for keeping it above the surface of the die is provided as shown in Fig. 8. The die member 24 is provided with a dovetailed slot 29 (see Fig. 7) arranged to fit a similar shaped tongue 30 on the die support 9 (see Fig. 2). This holds the die to the support. The die is further held by means of the screws 31. From the foregoing description of the various parts of the device, the operation thereof may be readily understood. The apparatus, as stated above, is for the purpose of embossing a heel on a shoe. The process of manufacturing the shoe will be completely set forth in a subsequent application Ser. No. 575,802 of even date. The novel shoe produced by this process has been made the subject-matter of another application Serial No. 575,803 also of even date. It is only necessary in the present case to indicate the operations connected with the machine itself, which forms the subject of the present invention. The rotatable die support 9 with the lower die is swung to one side. A shoe is now placed over the lower die. The rod 33, which is pivoted to the reduced portion 8^a of the post 8, is now drawn downwardly by pressing a foot lever (not shown) and the support 9 with the shoe upon it is then swung back until the stop 13 engages the arm 14. The rod 33 is released and the spring 10 forces the support upwardly so that the shoe is centered by means of the beveled sides of the die. I regard this preliminary means of centering the shoe as quite important. It will be seen that if the shoe should not be placed on the lower die in exactly the proper position, it will be moved to its proper position when the arm 9 is permitted to spring upwardly, this insuring an accurate adjustment of the shoe upon the lower die, and saving time which would otherwise be required for its proper adjustment. The post 6 is now forced upwardly, thereby moving the shoe against the upper die. The leather of the shoe, which has been previously moistened, is embossed so as to form a heel portion on the shoe. The pins 27 and 28 are guide pins for a pasteboard filling 34 (see dotted lines in Fig. 6) which is placed thereon. This filling is glued on its upper side and is maintained in position by means of the pins 27 and 28. When the heel is embossed, the

lower die forces this filler into the recess made on the inside of the shoe. The guide pins 27 and 28 are pushed inwardly against the tension of the springs 25, but return to their position when the operation is over 70 and the supporting arm 9 has been lowered. The arm 9 is now swung outwardly and the shoe is removed from the machine with the embossed heel and with the filler on its inner surface. 75

The reason why the channel 24^a is provided will be readily seen from an inspection of Fig. 1. This channel, it will be observed, is adjacent to the stitching, which sews the upper to the heel portion. Unless this channel is used the die is liable to cut the stitching, thereby injuring the shoe. In order to gage the depth of the portion to be embossed, I provide the adjustable set screws 17 and 18. It will be seen that by manipulating these screws the rear portion of the embossed heel, or the opposite front portion may be made higher or lower, according as the set screws are moved, the die member 19 being swung on its pivot 20. 90

The machine described above provides an efficient device for embossing heels rapidly, accurately and cheaply. The dies are securely held in place and may be replaced whenever it is necessary. 95

I claim:—

1. In a machine for embossing heels on shoes, a laterally shiftable support, a lower die mounted on said support and provided with a heel shaped surface arranged to enter the inside of an inverted shoe, an upper die having a heel shaped recess larger than the heel shaped surface on the lower die, and a spring for moving said lower die and the shoe against said upper die for adjusting the position of the shoe upon the lower die, the said support being capable of further movement for embossing a heel upon said shoe. 110

2. In a machine for embossing heels on shoes, a frame, a post slidably mounted in the frame and provided with an arm having a bore, a die support having a reduced portion extending through the bore in said arm for pivotally mounting the support, a spring arranged to bear on said frame for keeping said support in a normally raised position, a lower die carried by said support, said lower die having a heel shaped surface and provided with a recess around the edge of said surface, a pivotally mounted upper die having a heel shaped recess, and means for tilting said upper die on its pivot and for retaining it in its tilted position. 115

3. In a machine for embossing heels on shoes, a frame, a rotary die holder carried thereby, said die holder being provided with sockets, means for setting said die holder to bring all of said sockets successively into operating position, a die having a tongue 130

- adapted to enter said sockets, said die having an upper part integral with said tongue and a lower part pivotally mounted upon said upper part, means carried by said upper part for adjusting said lower part, the lower part having a heel shaped recess therein, and a lower die having a raised heel shaped surface and a groove around the edge of said surface.
- 5 4. In a machine for embossing heels on shoes, an upper die comprising two parts, a supporting part and a working part pivoted thereto, said supporting part having at its ends set screws adapted to bear on said working part for regulating the position of said working part with respect to said support, said working part being provided with a heel shaped recess, a lower die having a raised heel shaped surface, and a channel or groove along the edge of said heel shaped surface and being provided with spring pressed guide pins adapted to be pushed into said lower die when the latter is brought against the upper die.
- 10 5. In a machine of the class described, means for embossing a heel upon a shoe and means for simultaneously thickening the edges of said heel.
6. In a machine of the class described, means for embossing a heel upon a shoe and means for causing the shoe to be centered in the embossing means before the embossing operation begins.
- 15 7. In a machine of the class described, means for embossing a heel upon a shoe, comprising relatively movable dies, means for effecting the relative embossing move-
- ment of said dies, and means for effecting an initial shoe centering movement of said dies in advance of the relative embossing movement.
- 20 8. In a machine of the class described, means for embossing a heel upon a shoe comprising coöperating members one of which is constructed to press a permanent filler into the depression upon the inside of said shoe.
- 25 9. In a machine of the class described, means for embossing a heel upon a shoe and means coöperating with said embossing means for simultaneously locating a permanent filler in the depression upon the inside of said shoe.
- 30 10. In a machine of the class described, means for embossing a heel upon a shoe comprising relatively movable dies, one of which is located upon the inside of the shoe during the embossing operation, and means for holding a filler upon said last mentioned die constructed to permit said filler to attach itself to the shoe.
- 35 11. In a machine of the class described, means for embossing a heel upon a shoe comprising relatively movable dies, one of said dies being constructed to be located inside the shoe during the embossing operation and the other die being constructed to embrace the edges of the sole and to effect a vertical extension of said edges during the embossing operation.
